SPARK PLUG

Leo F. Lieser, Estherville, Iowa

Application October 2, 1934, Serial No. 746,565

2 Claims. (Cl. 123—169)

This invention relates to spark plugs for jump spark ignition systems.

A primary object of the invention is to produce a spark plug which will fire under obstinate oil 5 fouling conditions and under very high pressure.

Another object of the invention is to so construct a plug of this character that the inside will be kept clean and unfouled and in which the full surface of both electrodes will be used thus in- 10 ducing a very hot spark.

Still another object is to construct a spark plug in which the capacity of the compression chamber is decreased and a full ring fire spark created.

15 Another object is to construct a spark plug of this type having a spherical lower end or tip so that the two electrodes are at the peak or vertex of a sphere and thus accomplish a perfect spark.

Another object is to form a plug having a closed 20 lower end providing an internal resistance of its own against the motor compression and thereby keeping the inside of the plug clean.

In carrying out these objects the invention is 25 susceptible of modifications without departing from the spirit or sacrificing any of the advantages of the claimed invention.

In the accompanying drawing:

Figure 1 represents a side elevation partly in 30 section of a spark plug embodying this invention; Fig. 2 is a bottom plan view thereof;

Fig. 3 is a detail sectional view thru the electrodes, showing a slightly different form; and

Fig. 4 is a similar view of still another form.

In the embodiment illustrated a spark plug 35 is shown including the usual shell 1^a with an exteriorly threaded neck at 2 for mounting in the engine head, not shown. This neck 2 is threaded interiorly as shown at 3 to receive an adjustable end cap 10. Housed within the shell 1^a is the 40 usual porcelain insulator 4 which surrounds the central electrode 5 in the form of a pin which projects thru a central opening 11 in cap 10.

The cap 10 which constitutes one electrode of the plug also comprises the tip or lower end of 45 the plug and is substantially spherical in form since the jump spark of high tensioned voltage plugs is best accomplished thru spheres, the spark leaving same at the vertex. This cap 10 has its outer rounded surface cut away at 12 at opposite sides to form a grip for manipulating the cap to screw it into and out of the neck to insure correct adjustment for different spark gaps and for removing the cap in case of repair. This cap 10 50 which forms the lower end of the plug and encircles the electrode 5 provides a closed plug end producing an internal resistance of its own against the motor compression thereby keeping the inside of the plug clean and unfouled, and also causing

a decreased capacity of the compression chamber and creates a full ring fire spark entirely around the central electrode. Thus the full surface of both electrodes is used inducing a very hot spark. It will thus be seen that this is why this particular 5 plug will fire under obstinate oil fouling conditions since the oil cannot get to the interior of the plug. This plug will fire under very great pressure much beyond that where ordinary plugs cease.

It is to be understood that the cap 10 has a 10 tight screw connection with the neck 2 so that it will remain in adjusted position.

In Fig. 3 the aperture in the adjustable cap is shown flared to vary the spark gap; while in the form shown in Fig. 4 both the opening and the pin 15 are shown inclined for this purpose, the opening in Fig. 3 being numbered 11^a and in Fig. 4 11^b. The pin in Fig. 4 is numbered 5^a.

I claim as my invention:

1. In a spark plug the combination of a shell 20 interiorly screw-threaded at its inner end forming a portion of an electrode, an exteriorly screw-threaded cap engaged with the interior screw-threads of the shell and completing the electrode, the cap having an orifice centrally located and 25 gradually enlarging from the outer surface of the cap to the inner surface of the cap, an insulator within the shell, and a second electrode within the insulator having a projecting tapered end located centrally in the orifice of the cap, the end 30 of the inner electrode and the wall of the gradually enlarged orifice in the cap presenting differentially tapering surfaces whereby the spark-gap between the tapered electrode and the wall 35 of the orifice in the cap may be decreased or increased by screwing inwardly or screwing outwardly the cap.

2. In a spark-plug the combination of a shell 40 screw-threaded interiorly and exteriorly at its inner end, an insulator longitudinally located within the shell, an electrode having a projecting tapered inner end passing centrally through the insulator, a hollow centrally perforated hemispherical exteriorly screw-threaded cap to engage 45 the interior screw-threads of the shell the perforation in the cap being enlarged gradually inwardly from the outside surface of the cap to the inside surface of the cap forming a circular electrode surrounding the tapered end of the first named electrode, the end of the inner electrode and the wall of the gradually enlarged orifice in the 50 cap presenting differentially tapering surfaces diametrically opposite portions of the exterior surface of the cap being flattened to accommodate a manipulating tool whereby the spark-gap may be varied by screwing inwardly or outwardly the hemi-spherical cap.

LEO F. LIESER.
